JOHN EDWIN KILBURN, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

PEDESTAL.

1,184,102.

Specification of Letters Patent.

Patented May 23, 1916.

Application filed July 9, 1912. Serial No. 708,440.

To all whom it may concern:

Be it known that I, JOHN E. KILBURN, a citizen of the United States, residing at Philadelphia, in the county of Philadelphia and State of Pennsylvania, have invented 5 certain new and useful Improvements in Pedestals, of which the following is a specification.

This invention relates to pedestals and has 10 reference particularly to pedestals adapted for use in supporting car-seats. Such pedestals are commonly made of sheet-metal and consist of a base, usually of oval cross-section, and arms extending forwardly and 15 rearwardly from the upper end of the base and supporting the seat structure. Such a pedestal may be used for supporting the aisle end of a car-seat and the support of the wall end of the seat may be secured to 20 the car wall; if desired, however, two of the pedestals may be employed in supporting the seat one adjacent to each end of the seat.

The present invention is directed to the provision of an improved form of pedestal 25 so constructed that great strength is secured in a structure which is of light weight and so formed that it may be manufactured at comparatively low cost.

The improved pedestal possesses the further advantages that it is well adapted for 30 use as a support for the aisle end of a car-seat arranged adjacent to a trap door in the floor of a car, in which case the pedestal must be set inwardly from the end of the seat a substantial distance.

The preferred embodiment of the invention is illustrated in the accompanying drawings in which—

Figure 1 is an elevation of the pedestal, 40 Fig. 2 is an end view of the pedestal, Fig. 3 is a top view of the pedestal and Fig. 4 is a sectional detail view on line 4—4 of Fig. 1.

Referring to these drawings, the pedestal 45 consists of a base 1, of hollow sheet-metal and closed at its upper end. This base is preferably pressed into the form shown from a single piece of sheet-metal. It is of oval cross-section throughout and has a flaring base terminating in a flange 2. The 50 closed upper end of the pedestal is shown at 3.

The two arms of the pedestal are shown at 4 and 5, these arms extending forwardly and rearwardly from the upper end of the

base 1 as shown in Fig. 3. The arms 4 and 5 are both arranged on one side of the general plane of the pedestal, that is, both arms are arranged on the same side of a plane passing through the major axis of the oval of the base. Each arm is of inverted U-shape in cross-section, as best shown in Figs. 1 and 4, and the outer end of each arm is closed as shown at 10. Preferably each arm 4 and 5 is formed by pressing a piece of sheet-metal to the shape illustrated. After the two arms have been formed separately, as above indicated, they are secured together to form an integral structure as by welding their abutting edges together. The line of the welding is indicated by the dot and dash line on Figs. 1 and 3. The unitary structure constituting the two arms is then secured to the upper end of base 1 and this is also done by a process of welding. In preparing the base 1 for securing the arms thereto, the metal of the base 1 is cut along a horizontal line adjacent to the top 3 of the base as indicated by the line 6 on Fig. 1. This cut is preferably made by grinding the metal away at the junction of the top 3 of the base and the side wall of the base and in this way a notch or depression is formed at the top of the base which receives the edge of the metal of the arms at the junction of the two arms 85 on the side of the pedestal shown in Fig. 1. The base 1 is also cut on the opposite side thereof along a horizontal line adjacent to the top 3 as indicated by the reference 7 on Fig. 2, this cut extending substantially half 90 way around the top portion of the base, and having a slight depth below the top 3 as indicated at 7 in the figure. These two cuts having been made, the metal of the base 1 is preferably pressed inwardly along lines 95 extending vertically downward from the ends of the cut 7, as indicated at 8 on Fig. 3; these inwardly pressed portions extending downwardly for a suitable distance, say one inch, from the plane of the cut-away portion, or seat, 7. The base and the unitary structure including the two arms having been constructed thus and the outer side walls of the arms having downwardly extending edges 9 adjacent the portions which

100 seat on the cut-away part 7 of the base the two parts are assembled in the relation shown in the drawings, with the two edges 105

of the metal joining the two arms entering the cuts formed in the upper portion of the base 1 and the downwardly extending edges 9 of the non-adjacent sidewalls of the two arms extending downwardly along the outer sides of the base 1 and lying in the depressions 8. The abutting surfaces of the two pieces are then welded together. The welding covers the surface of the portions 9 of the arms which overlie the depressions 8 and also it extends along those edges of the arm-structure which enter the cuts formed in the base along the lines 6 and 7.

It will be seen that joining together the inner and outer flanges of the arms in the manner described, that is, welding together the abutting edges of the inner flanges 4' and 5', and of the outer flanges 4² and 5², of the inverted U-shaped arms, forms an interrupted or partial base portion for the combined arms, of substantially the same cross-section as that of the pedestal base at the top thereof.

When the parts have been assembled together thus a structure of great strength is provided and moreover, the structure is of light weight. The arms of the pedestal are extended a substantial distance to one side of the plane of the pedestal but the joint between the arms and the base is of such character that there is little or no danger of breakage at this point. By reason of the lateral extension of the arms 4 and 5, the base of the pedestal may be set in a substantial distance from the end of a car-seat while still supporting the seat structure at points substantially close to the aisle end of the seat. This pedestal may, therefore, be used in a car at a point where a trap door is provided in the floor of the car to give access to the underlying parts and permits of making the trap door of substantial size without having its removal obstructed by the pedestal.

The seat-structure is secured upon the ends of the arms 4 and 5 in any suitable manner. In the drawings, the ends of the arms are shown as having openings therein for bolts which bolts secure connecting rails to the ends of arms 4 and 5, these rails being employed for the support of the cushions and other parts of the seat.

Having described my invention, what I claim as new therein and desire to secure by Letters Patent of the United States is:

55 1. A pedestal comprising a hollow sheet-metal base and two sheet metal arms of inverted U-shape in cross-section secured together, to form an angle less than 180° between them, the inner flanges and outer flanges respectively of said arms being joined together to form an interrupted base portion for the combined arms, of substantially the same cross-section as that of the top portion of the pedestal, said arm base portion being seated in cut-away portions

at the top of the base, substantially as set forth.

2. A pedestal comprising a hollow sheet-metal base and two sheet-metal arms of inverted U-shape in cross-section secured together at their inner ends to form an angle between them, and secured to the upper end of the base to extend forwardly and rearwardly therefrom, said arms having their joined edges at opposite sides seated in cut-away portions at the top of the base, and having outer side portions intermediate said seated portions, extending outside of and secured to the metal of the sides of the base, substantially as set forth.

3. A pedestal comprising a hollow sheet-metal base having a top portion of curved cross-section, and two sheet-metal arms of inverted U-shape in cross-section secured together at an angle with the abutting edges of the metal at their inner ends joined to form a base portion for the combined arms of substantially the same cross-section as that of the said pedestal base, said arm base portion being seated in cut-away portions at the top of the pedestal base and having portions extending downwardly along the sides of the base and secured thereto, substantially as set forth.

4. A pedestal comprising a hollow sheet-metal base having a top portion of curved cross-section, and two sheet-metal arms of inverted U-shape in cross-section secured together at an angle with the abutting edges of the metal at their inner ends joined to form a base portion for the combined arms of substantially the same cross-section as that of the said pedestal base, said arm base portion being seated in cut-away portions at the front and rear of the top of the pedestal base, and having portions extending downwardly along the sides of the base and secured thereto, substantially as set forth.

5. A pedestal comprising a hollow sheet-metal base having a top of substantially oval section, and two hollow sheet-metal arms secured together to form an integral angular structure by securing together of the metal at their inner ends to form a base portion of like cross-section to that of the pedestal base, said arms being secured to the top of the pedestal base with portions of said arm base portion secured to the upper portion of said pedestal base, and said arm base portion having portions extending downwardly along the sides of the pedestal base, and secured thereto, substantially as set forth.

6. A pedestal comprising a hollow sheet-metal base and two sheet-metal arms extending forwardly and rearwardly from the upper end of the base and both arranged on the same side of the general plane of the pedestal, said arms being secured to the upper end of the base and having portions ex-

tending downwardly along the sides of the base and secured to the base, substantially as set forth.

7. A pedestal comprising a hollow sheet-
5 metal base and two arms of inverted U-
shape cross-section secured to the upper end
of the base, said base having vertically-dis-
posed depressions therein extending down-
wardly from the top thereof and said arms

having portions lying against the sides of the 10
base and entering said depressions, substan-
tially as set forth.

This specification signed and witnessed
this 5th day of July, 1912.
